[57] CLAIM

The ornamental design for a window lock mounting bracket, substantially as shown and described.

DESCRIPTION

FIG. 1 is a perspective view of a window lock mounting bracket showing our new design;

FIG. 2 is a side elevational view thereof;

FIG. 3 is a top plan view thereof, the bottom being substantially a mirror image of the top shown herein;

FIG. 4 is an end elevational view thereof;

FIG. 5 is an end elevational view thereof opposite to that shown in FIG. 4; and

FIG. 6 is a side elevational view thereof opposite to that shown in FIG. 2.

FIG-5

FIG-6
